UNITED STATES PATENT OFFICE.

OSCAR A. FELAND, OF BISMARCK, NORTH DAKOTA, ASSIGNOR OF ONE-THIRD TO VANCE J. WILSON AND ONE-THIRD TO THURMAN WRIGHT, BOTH OF BISMARCK, NORTH DAKOTA.

DRAWING HEAD.

Application filed September 9, 1925. Serial No. 55,396.

This invention relates generally to the art of making binder and other twines and has especial relation to means for preparing the fiber or sliver used in the manufacture of 5 twines, an object being to provide a drawing head which will be unaffected by atmospheric conditions and thus insure uniformity of "draw" and practically eliminate variation in the finished product.

10 Another object of the invention is the provision of a drawing head which will not pick up the fiber and carry it around the rolls, which frequently occurs with the use of leather aprons, while uniformity of tension 15 is maintained without frequent adjustment as is necessary when leather aprons are used.

Another object of the invention is the provision of a drawing head which, in addition to the above and other advantages, is constructed so that the number of bearings usually required for leather-apron heads are materially reduced and the power necessary for operation will be likewise reduced.

With the above and other objects in view, 25 the invention further includes the following novel features and details of construction, to be hereinafter more fully described, illustrated in the accompanying drawings and pointed out in the appended claims.

30 In the drawings:—

Figure 1 is a side elevation of a drawing head constructed in accordance with the invention and mounted in position for use, a fragmentary portion of a finishing machine 35 being illustrated.

Figure 2 is a fragmentary vertical sectional view of the same.

Figure 3 is a detail perspective view of the improved drawing head with parts 40 omitted.

Figure 4 is a detail perspective view of the sliver guide.

Referring to the drawings in detail wherein like characters of reference denote corresponding parts, the reference character 10 indicates a portion of the frame of a finishing machine of the character usually employed in the manufacture of twine, 11 the improved drawing head which is mounted 45 upon the machine frame and 12 the endless conveyor. The conveyor shown is of the usual type employed in machines of this character and may include iron cross rods which are studded with hackle pins and connected

by heavy metal links. The conveyor 12 may 55 be of any other suitable construction, its purpose being to feed the fiber to the drawing head.

The drawing heads now in common use include endless aprons or belts formed of 60 leather which pass around spaced rolls. These belts however are sensitive to atmospheric conditions so that frequent adjustment is necessary to maintain any uniformity 65 of draw. In addition, the belts are subject to great wear and must frequently be replaced. Further, these leather aprons pick up the fiber and carry it around.

The drawing head of the present invention overcomes these and many other disadvantages by providing a metal (preferably cast 70 iron) upper roll 13 and a pair of spaced lower rolls 14 which are also preferably of cast iron. The rolls 13 and 14 are preferably fluted and the lower rolls are relatively 75 small in diameter.

The lower rolls 14 are mounted in suitable bearings provided in a base 15 which is in turn mounted upon the frame 10, while the upper roll is mounted in adjustable bearings 80 16 which are slidable in spaced standards 17 rising from the base 15. The bearings 16 are yieldingly forced downward by means of springs 18 so that a yielding contact is provided between the rolls 13 and 14. The tension of the springs 18 may be regulated by 85 adjusting screws 19.

The shafts of the rolls 14 have mounted thereon gears 20 which are engaged by an idler gear 21, while one of the shafts of the 90 rolls 14 has mounted thereon a driving pinion 22 which operates the gear train 23 forming a part of the mechanism of the finishing machine.

The fiber is fed between the rolls 13 and 14 95 from the conveyor 12 by a guide 24 illustrated in detail in Figure 4 of the drawings. This guide comprises spaced supporting brackets 25 which are suitably secured to the machine frame and which are connected at 100 their outer ends by a bar or plate 26 over which the fiber or sliver passes to the rolls.

Each of the rolls 14 is provided with a wiper which includes an inverted substantially U-shaped frame 27 whose opposite side 105 arms are provided with elongated slots 28. Bolts 29 pass through these slots and engage the frame 10 so that the frames 27 will be

2

mounted for vertical sliding movement. Mounted upon each of the frames 27 is a wiper element 30 which engages one of the rolls 14 and prevents the fiber or sliver from 5 passing around these rolls. The wiper element is yieldingly forced into engagement with the rolls 14 by coiled springs 31 which surround bolts or studs 32 extending downwardly from the frames 27. The bolts or 10 studs 32 are mounted for sliding movement in brackets 33 secured to the frame 10, the springs 31 being interposed between these brackets and the frames 27. The tension of the springs 31 may be adjusted by nuts 15 34.

The improved drawing head as illustrated and described may be substituted for the drawing head now in use upon finishing machines and in addition to the many advantages above mentioned, the construction 20 of the head is such that knots and bunches in the fiber which pass between the rolls will attract the operator's attention so that all imperfections may be detected and corrected 25 and thus provide uniformity in the finished product.

The invention is susceptible of various changes in its form, proportions and minor

details of construction and the right is herein reserved to make such changes as properly fall within the scope of the appended claims.

Having described the invention what is claimed is:—

1. In a drawing head, an upper drawing roll, spaced lower relatively small drawing rolls associated with the upper roll, means to yieldingly force the rolls into contacting engagement, a guide plate spaced from the periphery of the upper drawing roll to guide 35 the fiber between the rolls and means to drive the rolls.
2. In a drawing head, an upper drawing roll, spaced lower relatively small drawing rolls associated with the upper roll, means 45 to yieldingly force the rolls into contacting engagement, means to drive the rolls and a yieldingly mounted wiper engaging one of the rolls, said wiper comprising an inverted substantially U-shaped frame, means to slidely support the frame, a wiper element carried by said frame and means to yieldingly force the wiper element to engage the 50 rolls.

In testimony whereof I affix my signature.
OSCAR A. FELAND.
